UNITED STATES PATENT OFFICE.

FRANK SCHRADER, OF CHICAGO, ILLINOIS.

STAMPING AND SEALING MACHINE.

Application filed May 2, 1925. Serial No. 27,566.

This invention relates to a device for stamping and sealing envelopes, the general object of the invention being to provide a receptacle in which the envelopes are placed, 5 means for feeding the envelopes one by one upon the conveyor and moistening the flaps as they pass to the conveyor, means for affixing stamps to the envelopes from a row of stamps and means for applying pressure to 10 the envelopes to cause the gummed portions of the flaps to adhere to the envelopes.

This invention also consists in certain other features of construction and in the combination and arrangement of the several 15 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation with parts in section of the device.

Figure 2 is a plan view.

Figure 3 is a section on line 3—3 of Figure 2.

Figure 4 is a section on line 4—4 of Figure 1.

Figure 5 is a section on line 5—5 of Figure 1.

Figure 6 is a detail view of one of the feeding disks for the envelopes.

Figures 7 and 8 are detail views.

Figure 9 is an end view showing the arrangement of the shafts.

In these views, 1 indicates a base and 2 indicating the various parts of the apparatus. An envelope containing receptacle 3 is supported from some of the uprights by a bracket 4, this receptacle being preferably formed of wire mesh with its lower part contracted at 45 its front, as shown at 3'. A frame 5 is placed around the upper portion of the receptacle and a pair of stub shafts 6 are carried by said frame, one at each side thereof and a disk 7 is fastened to each shaft, each disk having a 50 slit 8 therein with a portion adjacent the slit being curved upwardly and given a beveled edge, as shown at 9. These disks extend into the receptacle and will support

the envelopes, shown at A, therein and when the disks are rotated the beveled edges will 55 engage the lowermost envelope and separate it from the other envelopes and after the disks have made a complete revolution, the envelope will be freed from the disks and will drop to the lower part of the receptacle. 60 The stub shafts are provided with pulleys 10 which are connected by the belts 11 with the pulleys 12 on the cross shaft 13 carried by one of the uprights and said shaft is driven from a shaft 14 by means of the belt 65 15 and the pulleys 16 and this shaft 14 is in turn driven from a shaft 17 by means of the belt 18 and the pulleys 19 and the shaft 17 is driven from the conveyor shaft 20 by means of the belt 21 and the pulley 22. This 70 conveyor shaft 20 carries a roller 23 and a similar roller 24 is carried by the shaft 25 supported in uprights at the other end of the device. The conveyor belt 26 which passes over the rollers 23 and 24 is provided with 75 the strips 27 and said conveyor is arranged to pick up the envelopes discharged from the receptacle 3 and carry them to the stamp applying means.

As the envelope drops from the disk, it will 80 be caught by the pins 30 in the lower part of the receptacle and by a roller 31 which is arranged in a tank 32, this roller engaging the extended flap *a* of the envelope so as to moisten the same. The envelopes are held 85 on the pins by the jaws 60 on a rock shaft 61 which has a pinion 62 thereon engaging with a rack 63 which is reciprocated in its housing 64 by disk 65 on shaft 14 through the pitman 66. These parts are so arranged 90 that when the envelope drops upon the pins 30, the shaft will be rocked so that the projections 60 will grip the envelope between themselves and the pins 30. The envelope is knocked from the pins 30 and roller 31 by 95 a rod 33 which is carried by the pivoted arm 34, the arm and rod being given a rotary movement by means of the link 35 which is connected with the crank 36 fastened on the shaft 14. This rod 33 will first strike the 100 flap of the envelope and will fold the same over upon the rear of the envelope, causing the flap to pass over the moistening roller and causing the envelope to descend 105 upon the conveyor belt 26. Just as the rod 33 is moving the flap to closed position, the

- jaws 60 will be moving to open position so that the envelope will be released on the final movement of the rod so that the envelope can drop upon the conveyor. This belt 5 will then take the envelope to the stamp affixing means. Such means comprises a large roll 37 carried by the stub shaft 38 and having the notches 39 in its circumference which are spaced apart the distance of a stamp. 10 The strip B of stamps is placed on a roll 40 and the stamps are caused to pass over the roller 37 by means of the small roller 41 which presses the strip against the roller 37 and which is arranged in a tank 42 so that 15 it will moisten the stamps.

A small cutter roll 43 is arranged to cut the stamps from the strip at a point below the roll 41, the knife of such cutter roll engaging the notches 39. The severed stamps 20 will drop upon the envelope and then the envelope passes under the presser block 44 carried by the presser arm 45 which is normally pressed downwardly by the spring 46 placed on the stem 47 of the arm and pressing against a part 48 of the frame, the arm being raised by the cam 49 on the shaft 25 of the roll 24, the arm being provided with a small roller 50 for engaging the cam. A spring 51, placed on the stem 47 above the 25 part 48, tends to cushion the downward movement of the stamp affixer, this spring having less tension than the spring 46. This presser mechanism is arranged above the plate 52 carried by the frame so that the 30 portion of the envelope carrying the stamp is pressed between the block and this plate 52. This plate 52 directs the envelope between the presser rolls 53 and 53' which will press the flap firmly against the body of the 35 envelope and thus seal the envelope. The upper roll 53' carries the roll 40 for the strip of stamps and has its bearings pressed downwardly by the springs 54 which causes the roller 53' to be pressed against the roll 45 53 lower springs, 54' acting as cushion means for the parts. The rollers 53 and 53' are connected together by the gears 55 and the shaft of one of the compression rolls is connected to the motor 28 by the driving 40 connections 29 and the other shaft is belted to the shaft 25, as shown at 56. The roll 37 is belted to the roll 53', as shown at 56'.

From the foregoing it will be seen that the envelopes when placed in the receptacle 55 with their flaps in open position and the apparatus started up they will be fed one by one through the receptacle where their flaps are moistened and folded and then the envelopes will drop upon the conveyor and be conveyed to the stamp affixing device and then to the compression rollers where they will be sealed. Thus the device will automatically stamp and seal envelopes and at great speed.

60 Each pin 30 carries a spring 30' which

has a strip of rubber or the like at its upper end for engaging a jaw 60. The envelope is gripped between the jaws and the springs on the pins 30 and these springs would cause the jaws to grip the envelope before the 70 jaws touch the pins and they enable the envelope to be held by the parts a limited time after the jaws move away from the pins. This prevents the rod from interfering with the dropping of the envelope. 75

The rod 33 is attached to the link 35 by a spring 33' so that it is yieldingly supported. The spring will permit the rod to drop slightly toward the flap moistener and when the rod strikes said flap, it will give and pull 80 the flap under the envelope and turn the roller so that the roller is always moist.

It is thought from the foregoing description that the advantages and novel features of my invention will be readily apparent. 85

I desire it to be understood that I may make changes in the construction and in the combination and arrangement of the several parts, provided that such changes fall within the scope of the appended claims. 90

What I claim is:—

1. A device of the class described comprising a receptacle for holding envelopes, means for feeding the envelopes one by one from said receptacle, a conveyor for receiving the envelopes from the receptacle, means for moistening and folding the flaps of the envelopes just before they leave the receptacle, means for affixing a stamp upon each envelope, pressure rolls for sealing the envelopes and means for directing the envelopes between the pressure rolls as they leave the conveyor. 95

2. A device of the class described comprising a receptacle for holding envelopes, a pair of slotted disks, a receptacle arranged to hold the envelopes and to separate them one by one, supporting means for receiving the envelopes dropping from the disks, such means including a moistening roller for the flaps, means for causing the envelopes to drop from the supporting means and at the same time fold the flaps, a conveyor for receiving the envelope from the receptacle, stamp affixing means to which the conveyor carries the envelopes and pressure rolls for sealing the envelopes. 105

3. A device of the class described comprising a receptacle for receiving envelopes, a pair of slotted disks in the receptacles arranged to hold the envelopes therein and to separate them one by one, supporting means in the receptacle for receiving the envelopes from the disk, such supporting means including a moistening roll, means for folding the flaps of the envelopes and causing them to drop upon the supporting means, a conveyor for receiving the envelopes from the receptacle, a stamp affixing device to which the conveyor carries the envelopes. 115

velopes, such means including a feed roller, means for causing a strip of stamps to pass over the roller, means for moistening the stamps as they pass over the roll, a cutter for 5 cutting the stamps from the strip, a pressure arm for pressing the stamps upon the envelope, spring means for giving the arm its

pressing action, cam means for raising the arm and presser rollers for receiving the envelopes from the stamp affixing means for 10 sealing the same.

In testimony whereof I affix my signature.

FRANK SCHRADER.
